CLAIM

The ornamental design for a parking kiosk, as shown and described.

DESCRIPTION

FIG. 1 is a front perspective view of a parking kiosk according to an exemplary embodiment of the present design;

FIG. 2 is a right elevational view of the parking kiosk shown in FIG. 1;

FIG. 3 is a left elevational view of the parking kiosk shown in FIG. 1;

FIG. 4 is a front elevational view of the parking kiosk shown in FIG. 1;

FIG. 5 is a rear elevational view of the parking kiosk shown in FIG. 1;

FIG. 6 is a top plan view of the parking kiosk shown in FIG. 1; and,

FIG. 7 is a bottom plan view of the parking kiosk shown in FIG. 1.

The broken lines in the figure drawings illustrate portions of the Parking Kiosk that form no part of the claimed design.

1 Claim, 5 Drawing Sheets
